TORCH FOR REMOVING DEFECTS FROM
BILLETS

Edward H. Hendricks, Poland, Ohio

Application December 8, 1930, Serial No. 500,740

5 Claims. (Cl. 158—27.4)

The present invention relates to the treatment of steel billets and ingots for the purpose of removing surface defects such as scabs, seams, lapped metal, or cracks caused by the cooling and shrinking of the billet, which, if not removed prior to the subsequent rolling operations, are inimical to the finished products such as sheets, plates, bars, or the like into which the metal of the ingot is ultimately formed.

10 It has heretofore been the practice to remove defects of the character aforesaid by chipping them out with hand or air operated chisels in such manner that a relatively wide and shallow groove or depression is formed in the ingot adjacent to the place at which the defect existed, a 15 groove or depression of this character being substantially unobjectionable during the subsequent treatment of the ingot as it is not reproduced or does not otherwise show up in the finished product as does a narrow and relatively deep crack or fissure. However, this method of removing defects is objectionable because of the amount of time and labor required, so that attempts have been made to cut out the defects with a gas cutting torch of ordinary construction and thus 20 adapted to produce a cylindrical or pointed flame which necessarily causes a narrow deep cut or groove in the ingot the sides of which must thereafter be tapered or flared upwardly and outwardly 25 from the bottom to the surface of the ingot to thereby bring the cut to the approximate shape or form of the depressions resulting from the use of hand chisels in order to prevent it from appearing in one form or another in the finished 30 product. Thus, while the time and labor requisite for actually cutting out the defect is decreased by the use of an ordinary gas cutting torch, the saving is largely offset by the necessity for thereafter suitably shaping the cut or fissure formed 35 by it in the metal, so that the ultimate saving effected over the use of manually or air operated chisels is not so great as might at first appear.

Therefore, an object of my invention is to provide a novel method of removing surface defects 45 from billets and ingots with much greater rapidity than is possible when manually or air operated chisels or the like are employed, yet which results in leaving the billet in condition for further rolling or other operations without the necessity 50 for dressing up the sides of the cut or depression formed in the vicinity of the defect when the latter is cut out.

A further object of the invention is the provision of a novel form of cutting torch adapted for 55 the performance of the method of my invention

and which is simple in construction, comparatively cheap to manufacture, readily operable in the hands of a workman of ordinary intelligence, and which is effective to deliver a flame of predetermined shape capable of cutting the billet in the 60 vicinity of the defect with an action akin to that of a chisel or a gouge, with resultant production of a depression in the surface of the billet which is relatively shallow in comparison to its width and thus not of a character to produce defects in 65 the articles into which the billets may subsequently be formed.

Other objects, operations, advantages and novel features of design, construction and arrangement comprehended by the invention are herein-after more particularly pointed out or will be readily apparent to those skilled in the art from the following description of the practice of the method by the use of torches of the character of those to which reference has just been made. 75

However, I desire it to be understood that the practice of my improved method of removing surface defects from billets and the like is not restricted to the use of the particular forms of torches hereinafter disclosed, although I have 80 found in practice that they are well adapted therefor and their use will consequently be generally preferred.

In the said drawings, in Figs. 1 to 5 inclusive I have shown one form of my improved torch, 85 and in Figs. 6 to 11 another form thereof, certain of the figures in each case being designed to illustrate the preferred manner of making one of the constituent parts of the torch. More particularly, Fig. 1 is a central, longitudinal section of the 90 first form as it appears when assembled for use; Fig. 2 is a central longitudinal section of the partially finished blank from which the torch tip is preferably constructed; Fig. 3 is an end view of the completed tip, and Figs. 4 and 5 are respectively sections thereof on lines 4—4 and 5—5 in Fig. 3 looking in the directions indicated by the arrows. The other form of the torch to which I have referred is illustrated in the other figures, 95 of which Fig. 6 is a view of the assembled torch in central longitudinal section and thus generally corresponding to Fig. 1; Fig. 7 is a front end view thereof. Fig. 8 is a view partially in elevation and partially broken away into section of the partially finished blank from which the torch 105 tip is preferably constructed; Fig. 9 is a side elevation of the completed tip; Fig. 10 is a central section of the latter on the line 10—10 in Fig. 9 looking in the direction of the arrows, and Fig. 11 is a central section of the tip cover removed 110

from the tip connector and tip. Similar symbols of reference are employed to designate corresponding parts in the several figures.

- Referring now more particularly to that form 5 of the torch illustrated in Figs. 1 to 5 inclusive, it will be noted from Fig. 1 that the torch includes four separable elements, to wit, a head H, a tip connector C, a gland G, and a tip T. The head 10 comprises a body 1 of suitable external contour and having a laterally directed neck 1' adapted for the reception of three tubes 2, 3, 4, through the first of which oxygen at high pressure, through the second of which oxygen at a lower pressure, and through the third of which acetylene 15 or other gas is supplied to the head. Within the head, passages 2', 3', 4' are arranged to conduct these gases from the several pipes toward the center of the head which is bored out to form a generally conical socket for the reception of the 20 correspondingly cone-shaped end 6 of the connector C which is integral with the generally cylindrical body 7 of the connector extending coaxially from the end 6 and of less diameter than the latter with resultant formation of a shoulder 25 8 against which the inner end of the annular gland G abuts when the parts are assembled, the gland being threaded into the larger end of the opening in the head so as to maintain the connector and head in proper operative assembly and 30 effect a sealing contact between the conical end of the connector and the wall of the conical bore in the head.
- The tip connector has an axial bore 10 which, adjacent its outer end, may be taper reamed as 35 shown, while the head 1 adjacent the end of this bore may be cored out to provide a chamber 11 communicating with the inner end of the passage 2', thus enabling the high pressure oxygen from the tube 2 to pass into the bore 10 in the 40 tip connector.
- Adjacent the inner ends of the passages 3', 4' annular grooves are respectively formed in the wall of the conical bore in the head and corresponding grooves respectively aligned therewith 45 are provided in the surface of the conical end of the tip connector so that separate annular chambers 12 and 13 are provided into which low pressure oxygen from tube 3 and the acetylene or other gas from the tube 4 can pass. From the 50 chamber 12 a plurality of small holes or passages 14, desirably symmetrically annularly spaced, are extended in the tip connector to its outer end and a short hole or passage 15 extended from each of them to the annular chamber 13 with the 55 result that the low pressure oxygen and acetylene can enter the passages 14 and, while mixing together therein, pass to the outer extremity of the tip connector upon the adjacent end of which is supported the tip T, desirably by providing the 60 latter at its rear end with an internally threaded bore 20 cooperative with the correspondingly threaded end of the tip connector, thus permitting the tip to be readily assembled on or removed from the latter.
- The tip connector and tip are both desirably 65 formed of copper, brass or the like and the former so arranged as to deliver a substantially chisel-shaped or fantail flame, and while various means and methods may be employed in the construction of the tip I prefer to form it from a 70 cylindrical blank in the following way: The blank, which is of greater diameter than the finished diameter of the tip, is first centrally bored from one end to the other and then taper-reamed to 75 provide a conical hole extending inwardly from

one end of the blank for a considerable distance and having its larger end adjacent thereto. I then counterbore the opposite end of the blank coaxially with the conical bore to approximately the diameter and length of the threaded end of the tip connector, the conical bore and counterbore being respectively designated as *a* and *b* in Fig. 2, which shows the blank at the conclusion of these operations. The end of the blank adjacent the larger end of the bore *a* is subjected to pressure at opposite ends of a diameter, conveniently by placing the end of the blank between the jaws of a vise, until the mouth or end of the bore is reduced to substantially the form of an ellipse in which the major axis is approximately four times the length of the minor. The blank is then removed from the vise or other machine through which the pressure was applied and turned or otherwise machined to the desired finished diameter and the counterbore *b* threaded and finished at its inner end so as to provide a generally annular chamber 21 from which a plurality of annularly spaced small passages or holes 22 are drilled through to the extremity of the burner, the arrangement and disposition of these holes 100 being preferably substantially as shown in Figs. 3, 4 and 5. By these several operations a tip of the character of that illustrated in the said figures may be readily formed, and from an inspection thereof it will be noted that extending from the 105 chamber 21 at the inner end of the threaded counterbore it embodies a central passage 23 (desirably reamed to cylindrical form after the completion of the compressing operation on the tip) approximating in diameter the outer end of the 110 passage 10 in the tip connector and merging at its outer end into a generally fan-shaped orifice or nozzle opening 25 of substantially elliptical cross section which terminates at the outer end of the tip, this orifice being in effect surrounded 115 by the extremities of the passages 22 forming ports 22' and certain of which are desirably disposed more nearly adjacent the orifice than others thereof, as best shown in Fig. 3.

With the parts constructed and assembled 120 substantially as described, it will be apparent that when the torch is in operation, oxygen under high pressure is admitted from pipe 2, which is suitably valve-controlled, to the passage 10 and thence passes into the central passage in the tip and is 125 ejected therefrom in a form determined by the configuration of the orifice or nozzle 25; at the same time the oxygen under low pressure and the acetylene respectively pass into the annular chambers 12 and 13 and thence through the passages 14 into the annular chamber 21, being mixed together in the passages and also in the chamber. From the latter the oxy-acetylene mixture is discharged at the end of the tip through the ports or passages 22' and after ignition thus forms a 130 plurality of preheating flames surrounding the main oxygen discharge from the elliptical orifice 25. The tubes 3 and 4 are desirably valve controlled and the oxygen supplied by the latter is conveniently bled from the main oxygen supply 140 through a reducing valve so as to enter the burner at a pressure of about ten pounds per square inch while the main supply of oxygen desirably enters at a pressure of about fifty pounds per square inch.

A torch of the character of that just described is capable of supplying a substantially fan-shaped or chisel-like flame by means of which a relatively wide and shallow cut can be readily taken in the surface of a billet or ingot adjacent a de- 150

fect therein so as to remove the latter and leave a correspondingly wide comparatively shallow depression in the surface of the metal which does not injuriously affect or show up in the articles ultimately formed thereof, so that by the use of the torch the surface defects in the ingot may be very rapidly and satisfactorily removed, while the necessity for dressing up or re-shaping the cuts formed by the torch is entirely obviated.

10 In Figs. 6 to 11 I have shown another form of torch constructed in accordance with my invention and adapted to produce a flame which operates on the ingot very much as an ordinary carpenter's gouge operates on a block of wood 15 and consequently tends to form a depression relatively wide in comparison to its maximum depth, the sides of which curve upwardly in opposite directions to meet the surface of the billet, a cross section of the depression thus approximating 20 the segment of a circle. In general, the construction of the head H and gland G are similar to those hitherto described and reference thereto would therefore be superfluous, but the tip connector C' is made much shorter and at its outer 25 end is externally threaded for the reception of a sleeve S, correspondingly internally threaded at its inner end, and is also counterbored adjacent the end of the passage 10 and internally threaded to receive the correspondingly externally 30 threaded end 30 of the tip T'.

The latter, as well as the tip connector and sleeve, is desirably formed of copper or brass and preferably from a blank of the general shape of that shown in Fig. 8, comprising a cylindrical 35 neck c having at one end an enlarged annular head d and centrally bored from one end to the other to provide a conical tapered passage b. The head of this blank during the manufacture of the tip is subjected to pressure along a diameter substantially in the manner heretofore described until it assumes a generally elliptical cross section with its longer axis considerably in excess of its shorter. Thereupon, a reamer of greater diameter than the minor axis of the 40 ellipse at its outer end is run through the blank coaxially with the undeformed part of the bore b and the outside of the tip when turned or otherwise brought to a cylindrical contour with the extremity or outer end 31 of the tip of slightly 45 greater diameter than the body 32 thereof as best shown in Fig. 9. As a result a nozzle opening 33 is formed at the end of the tip which is circular in cross section at the center but has a pair of diametrically opposed slots or channels 50 34 respectively disposed on opposite sides thereof, these channels being formed by the extremities 55 of the elliptical opening resulting from the crushing of the head of the blank.

The enlarged end 31 of the tip is provided with 60 a plurality of small passages 35 extending from the shoulder presented at its juncture with the body 32 to its outer end and there forming ports 35', these passages and ports being annularly spaced about the central opening and desirably 65 arranged substantially as shown in Fig. 7, and corresponding in function to that of passages 22 and ports 22' already described.

When the tip is assembled on the connector C', it is, as hitherto stated, screwed into the internally threaded end thereof and the sleeve S 70 is then disposed over the tip and screwed down over the externally threaded end of the connector. This sleeve is designed to snugly receive the head 31 so as to prevent any material leakage of gas between the parts at this point and

may be enlarged slightly in internal diameter in line with the body of the tip so as to provide, when the parts are assembled, an annular mixing chamber 37, and a plurality of small passages 38 are drilled in the sleeve so as to extend from the outer end of this chamber to the extremity of the sleeve, these passages supplementing the passages 35 and of course being spaced farther from the axis of the tip.

It will thus be apparent that in this form of the invention the high and low pressure oxygen and the acetylene or other gas enter the head in the manner hitherto described, and that the high pressure oxygen thence passes through the passage 10 and the central passage 39 in the burner tip to emerge through the peculiarly shaped nozzle orifice 33 which is effective to so form the flame that it is capable of exerting a gouging action on the metal of the ingot as already stated. The low pressure oxygen and acetylene, passing respectively into the annular chambers 12, 13, are thence delivered by the passages 14 to the annular mixing chamber 37, whence they pass through the passages 34 and 38 and produce a plurality of small flames which 100 act as preheating flames and surround the central flame or jet.

It is thus apparent that by the use of either of the forms of torches which I have described it is possible to speedily and satisfactorily remove surface defects from ingots, billets or the like without leaving fissures, cracks or cuts therein of such character as to be objectionable in the subsequent operations to be performed thereon or which will result in imperfections in the finished articles ultimately produced from the ingot metal, the results of the method in this respect corresponding to those of the hand chisel or air chisel chipping methods heretofore generally employed; on the other hand, the saving in time 115 and labor in removing the defects from the billets through the medium of my invention is enormous over the said prior methods with resultant reduction in production costs. Moreover, the torches of my invention are simple and satisfactory for the performance of their intended function, do not readily get out of order under the conditions of use to which they are necessarily subjected, and finally, can be operated by 120 workmen of ordinary intelligence with entirely satisfactory results after a minimum amount of instruction.

While I have herein described with considerable particularity certain forms of torches constructed in accordance with my invention, I do 130 not thereby desire or intend to limit or confine myself to any precise details in the design, method of assembly and/or arrangement of the various parts as the same are capable of modification and variation in numerous particulars if desired without departing from the spirit and scope of the invention, while the practice of my improved method, though capable of efficient and satisfactory performance with torches of the character of those to which I have referred, is in no way limited thereto and may be carried out by means of other instrumentalities if preferred.

Having thus described my invention, I claim and desire to protect by Letters Patent of the United States:

1. A gouging torch of the class described comprising a head, a tip connector removably seated therein, means for maintaining the connector in assembled relation with the head, a tip removably seated on the end of the connector and hav-

- ing a nozzle orifice of substantially elliptical cross section the walls of said orifice intersecting in acute angles at the extremities of its line of greatest dimension and a plurality of ports 3 each of relatively smaller area than the orifice disposed thereabout and extending angularly outwardly with respect to the axis of the tip, means for conducting a mixture of air and gas to each of said ports, and means for conducting gas 10 to said orifice providing a cylindrical passage communicating therewith, the diameter of said passage being greater than the smaller dimension of the orifice and less than its greater dimension.
2. In a gouging torch of the class described a 15 tip having a substantially elliptical nozzle orifice the oppositely curved bounding edges of which intersect in acute angles at the ends of its major axis, said tip being adapted to discharge a stream of gas of substantially elliptical cross sectional form, a plurality of spaced ports adjacent the orifice and each of smaller effective area than the effective area of the orifice and passages terminating in said ports extending angularly outwardly with respect to the axis of the tip.
3. A gouging torch of the class described comprising a head, a tip, and an element connecting the head and the tip, said element and said tip forming a passage terminating at the end of the tip in a substantially elliptical discharge 20 orifice, the oppositely curved bounding edges of said orifice intersecting in acute angles at opposite sides of the tip, said angles forming the extremities of the greater dimension of the orifice, said tip also having a plurality of divergent 25
- 35
- passages terminating in ports spaced from the orifice and from each other, and means for conductin an ignitable gaseous mixture to the passages.
4. A gouging torch of the class described comprising a head, a tip connector having one end seated therein, means for maintaining the connector in assembled relation with the head, a tip carried by the connector and having a nozzle orifice bounded by curved edges intersecting in acute angles at the ends of its line of greatest dimension, the central portions of said edges forming arcs of a circle, a sleeve surrounding the tip and arranged to provide a mixing chamber between the tip and the inner wall of the sleeve and a plurality of outwardly divergent passages extending to the end of the tip from said chamber, the ends of said passages being spaced from the nozzle orifice, and means for introducing gases respectively into said chamber and said orifice. 80
5. In a gouging torch of the class described, a tip having a nozzle orifice bounded by oppositely curved edges intersecting in acute angles at the ends of its line of greatest dimension and adapted to impart a gouge-shaped contour to a flame produced by combustion of a gaseous fluid issuing therefrom, means for conducting gas to said orifice, a plurality of ports arranged about the orifice and spaced therefrom and from each other, 85 and means providing a plurality of divergent passages adapted to conduct gases to said ports. 90
